GAS PUMPING

Johann J. Wydler, Westfield, N. J., assignor, by
mesne assignments, to Cities Service Oil Company,
New York, N. Y., a corporation of Pennsylvania

Application November 12, 1938, Serial No. 240,015

20 Claims. (Cl. 230—69)

This invention relates to gas pumping, and has particular reference to improvements in method and apparatus for utilizing the potential energy of hot gases under low pressure for producing 5 flow of cold gases.

A particular object of the invention is to provide a novel way for utilizing the potential energy which is available in the hot waste exhaust gases discharged from an internal combustion engine.

10 Another object is that of providing method and means for efficiently converting the pressure and temperature energy of one hot body or stream of gas into kinetic and pressure energy of other cold gas bodies.

15 A particular feature of the invention resides in a novel form of apparatus which may be broadly termed a gas displacement and breather pump. Essentially this apparatus consists of a wall-enclosed vessel having valved gas inlet ports at both

20 top and bottom and having a bottom gas outlet and a cooling element. The pump is so arranged and operated that hot engine exhaust gases, for example, may be introduced under pressure into the top of the vessel originally filled with air or

25 cold gases, thereby imparting pressure and kinetic energy to the cold gases which are displaced and forced out of the bottom of the pump by the hot gases, while the hot gases are expended to atmospheric pressure; after which the hot

30 gases are cooled as by recuperative heat transfer and undergo a shrinkage in volume which is sufficient to allow the breathing into the bottom of the vessel of cold air or gas flowing from some external source. The masses of cold gases put

35 into motion under definite pressure differentials during discharge and suction intake periods afford means to transform the energy lost by the exhaust gases during the discharge and intake periods into useful mechanical work indirectly,

40 as by means of a turbine wheel.

In so doing, the operating cycle may be actually continued into the ranges below atmospheric pressure with all its beneficial consequences for utilizing the lower heat ranges. Such procedure

45 of course would always be impractical with any mechanical piston apparatus.

The exhaust loss which usually is involved in standard operation of internal combustion engines consists mainly of two major portions.

50 The first portion is represented by the waste of potential pressure energy which discharges the cylinder content to the outside at a high rate of speed without doing any mechanically useful work. The other portion is the great amount of intrinsic heat still contained in the exhaust gases

after they have reached pressure balance with the outside atmosphere, and which in such form represent a great amount of useless and degenerated heat energy.

It is therefore a feature of the invention to provide 5 a displacement and breather type pump which makes it possible to utilize both of these portions of the exhaust energy of an internal combustion engine.

Another object of the invention is to provide 10 a method and apparatus for compressing and pumping air or other gas without the use of expensive mechanical means. Such air may be used for supercharging an internal combustion engine.

Further objects and advantages of the present 15 invention will be apparent from the following description taken in connection with the accompanying drawing, in which:

Fig. 1 is a pressure-volume diagram illustrating 20 the variation in absolute pressure combined with the movement of the gas fronts inside a displacement and breather type pump over one complete cycle;

Fig. 2 shows diagrammatically the change in 25 gas weights occurring during one complete cycle;

Fig. 3 is a diagrammatic view showing the arrangement of the cooling apparatus and valves at the period 20 (Fig. 1) of the cycle of the pump;

Fig. 4 is a diagrammatic view showing the hot 30 gas inlet valve open during the admission period 20—22—24 of the cycle;

Fig. 5 is a diagrammatic view showing the relative positions of the cooling apparatus and valves at the end 24 of the admission period 20—22—24.

Fig. 6 is a diagrammatic view showing the 35 closed position of an inlet valve for the cold air and the open position of an outlet valve for the cold exhaust during the discharge and expansion period 22—24—26;

Fig. 7 is a diagrammatic view showing the relative positions of the cooling apparatus and valves at the end 26 of the discharge and expansion period 22—24—26;

Fig. 8 is a diagrammatic view showing the 40 positions of the inlet valve for the cold air and the outlet valve for the cold exhaust during the condensation period 26—28;

Fig. 9 is a diagrammatic view showing the 45 positions of the cooling apparatus and valves during the cooling period 28—29—30;

Fig. 10 is an end vertical sectional view of a 50 preferred design of pump showing the cooling apparatus and valves;

Fig. 11 is a side vertical sectional view of the 55 pump of Fig. 10, with parts shown in elevation.

Fig. 1 displays the PV diagram of the cycle of a pump 32 (Fig. 10) having a valved gas inlet 36 at its top which may be directly connected to the exhaust manifold 48 of an internal combustion engine (not shown), and preferably having sufficient gas storage capacity to hold the exhaust gases discharged from the engine cylinders during several combustion cycles or over a period of several seconds. Following up the movement of the gas fronts, an indicator card (Fig. 1) is obtained which in many respects has the characteristics of a normal card of a piston engine with outside admission. The upper part of the card from 20 to 26 demonstrates the compression and displacement period of the cycle, and the lower part from 26 to 30 demonstrates the cooling and breathing period.

In Fig. 2 the same numerals as in Fig. 1 are used and terminate the same cyclic steps; the ordinates, however, indicate the gas weights involved inside the pump expressed in multiples of exhaust gas weight available from the engine. The values hold true for a definite example with a maximum pressure height of two atmospheres absolute and 1600° F. absolute exhaust temperature. However, the scope of the invention is not to be limited by these numerical values.

It has long been known that gases of different temperature, because of their different densities, maintain stratified layers. Such a stratification is only nullified or disturbed if the whole volume of the hot and cold gas masses is put into a state of more or less violent motion. If the volumetric capacity of the pump container is chosen of such magnitude as to be a large multiple of the unit volumes of individual exhaust gas discharges from engine cylinders, the velocity of influx is easily reduced as by baffle plates so as to prevent violent intermixing between the cold air and the hot gases. Such stratification is not disturbed if the hot exhaust gases are acting not only as a displacer pushing the cold air which originally occupied the pump out of the pump, but if they are simultaneously compressing the cold air before or while any discharging takes place. The number of exhaust gas discharges which are to be dealt with inside of the pump, or the relative volumetric capacity of the pump, is largely determined by the time required for the efficient cooling of the hot gases during the later cooling period of the cycle.

Analyzing the cycle diagrams of Figs. 1 and 2 in detail, we are dealing with a cycle either of best efficiency or of greatest power capacity, depending on whether we operate the cycle along the expansion curve 24 to 26 or along the broken line 24—25—26. In both cases, during the period 22—24 the same proportion of cold gas content is discharged under the full pressure potential ΔP , represented by 21—22. Consequently the remainder of cold gas discharge also involves equal weights whether we operate along 24—26 or along 24—25. With the first method of best efficiency the remainder of the cold gas content flows out under a changing pressure differential, dropping from ΔP to zero. In the second case of greatest capacity, it is pushed out under the constant differential ΔP , maintaining its full magnitude to the end at 25. Obviously the cold gas carries with it a maximum amount of energy when discharged under the second method. The first method of discharge 24—26 requires a time period essentially longer than the second method 24—25. A correspond-

ing saving in operating time is utilized conveniently, as explained hereafter.

Another difference in operation affects the weights of the incoming hot exhaust gases involved. With the first method admission of hot exhaust gases into the pump terminates at 24. With the second method it must be continued beyond 24 and maintained up to 25. The first case presupposes that admission of exhaust gases is stopped at a point 24 so as to yield a final expanded volume of the exhaust gases at 26 just occupying the total pump volume at atmospheric pressure. Thus the admitted exhaust gases return according to this method of operation the maximum of expansive working capacity, illustrated by the area 21—22—24—26. Therefore this case represents the cycle of best efficiency. With the second method, the pump is again completely filled with hot gases at 25, which, however, are under higher pressure and therefore represent a greater weight, indicated by the ordinate 28—25 in Fig. 2, as against 28—26 pertaining to the first method.

With the first method, the exhaust gases at 26 have reached a balance with atmospheric pressure and may be subjected immediately to the cooling process in order to make their remaining intrinsic heat do further work. Under the cooling influence, the exhaust gas shrinks and the pressure is lowered at 28 to about one-third of an atmosphere. By admitting fresh air from the outside as for example by way of a nozzle and a turbine wheel, this partial vacuum is gradually filled up along the curve 28—30, with full atmospheric balance restored at 30. The curve 28—30 may be interpreted as an average isothermal compression curve. The pump content at 28 has almost atmospheric temperature. During the compression 28—30, this temperature has a tendency to rise adiabatically. On the other hand, the outside air drawn into the pump may be cooled down adiabatically below its initial outside atmospheric temperature while passing through a turbine nozzle. Such refrigerating effect more than compensates for the adiabatic heating effect during the compression 28—30.

With the second method, the cycle may proceed from 25 in three different manners. By releasing the excess exhaust gas inside the pump to the outside atmosphere, the total mass of hot gases would expand to a point 27 with an amount corresponding to 20—26 left inside the pump and 26—27 being pushed out into the open atmosphere. Of course, the expansive work 25—26—27 would be sacrificed to the outside. From there on, the cycle proceeds with the portion 20—26 as in the first method.

Another possibility would be to begin cooling without discharge to the outside. Such procedure however would result in appreciable loss of suction intake work 26—28—30. The lowest pressure in this case would be about two-thirds of an atmosphere absolute, as against one-third atmosphere absolute with the first method, and correspondingly much less air could be taken in from the outside.

As a more economical and third possibility applicable in all practical cases where, within a power plant, a number of pumps 32 (two or three) are operated in cyclic phase, the first pump is connected after period 25 to the next one, thus utilizing the discharge of hot gases from one pump for effecting at least part of the initial compression 20—22 of the next pump. Thus the pressure 25 drops to somewhere half-75

way between 25 and 26, and we may now sacrifice only a small portion of expansive work of the same character as 25-26-27, which is compensated for by a corresponding saving in compression 28-29-22 in the next pump. These two additional cyclic functions may readily be handled within the time interval saved during the more rapid full pressure discharge 24-25.

The working of the cycle so far as the gas weights are concerned may now be followed through with reference to Fig. 2. The ordinate at 20 in this example indicates that cold gases are present inside the pump to the extent of three units of the weight of hot gas which is to be admitted to the pump as the exhaust of the engine for operating one pump cycle. At 22, the same three units are still inside and part of another unit is added as hot exhaust. Beginning from 21 down to 26, the cold gas is discharged in a linear function. However, from 22 to 24 more hot exhaust gas is added until at 24 it reaches the magnitude of a full unit weight 23-24. From there on the exhaust gas weight remains constant when working along the best efficiency methods while the cold gas content decreases to zero, with the result that at the end only the one unit of exhaust gas remains inside the pump represented by the ordinate 26-28. If on the other hand, the pump is operated along the cycle 24-25-26, the unit weight of exhaust gas at 24 is still augmented to the total of 25-28 at the end of the discharge period. There it is reduced to 26-28 by disposing of the excess 25-26 first into the next pump, and the rest to the atmosphere.

During the shrinking process from 26-28 in Fig. 1, the weight of gases inside the pump is not changed and they remain inside during the entire intake process. However, during this intake 28-30 (Fig. 1) outside air is sucked back into the pump until at 30 it is again filled up with three units of weight, made up of one unit of cooled exhaust 30-33 identical to 26-28 (Fig. 2), and two units of fresh intake 30-31, (Fig. 2). At this point the pump is ready to initiate a new cycle of operation beginning at 20.

Thus the working principle of the pump can be summarized in simple terms as follows: one unit of exhaust gas weight is adapted to discharge three units of cold gases which may flow by way of a turbine nozzle and turbine wheel, and thereafter to draw back into the pump two other units of outside gases until the total intrinsic heat of exhaust gases above atmosphere is completely utilized for doing such displacement work. Thus the breather pump can be interpreted as a "thermodynamic transformer" which utilizes a given weight of hot exhaust gas to move a multiple weight of cold gases through the same pressure differentials. With such apparatus a very convenient medium for doing work on a turbine wheel operating at atmospheric temperatures is provided with moderate pressures and speeds of flow, and with relatively large amounts of gas weight. These ultimate objects of the invention are dealt with in detail in my copending application S. N. 240,017 filed concurrently herewith for "Gas turbine system."

Figs. 3 to 9, inclusive, show diagrammatically the cycle of the breather pump. At the beginning of this cycle, that is at instant 20 in Fig. 1, the pump 32 is filled with cold gases consisting of previous exhaust gas cooled down and fresh air at atmospheric pressure. The exhaust

gas cooled down may be considered as occupying substantially the upper third of the pump above an imaginary dividing line 34 (Fig. 3), with the cold air occupying the space below the dividing line 34. At this instant an inlet valve 36 for hot exhaust gas, an inlet valve 38 for cold air, and an outlet valve 40 for cold exhaust gas are all closed, and a cooling unit 46 is in its neutral position.

The admission period (Fig. 1) corresponds to the line 20-22-24. During this period the admission valve 36 is kept open as shown in Fig. 4 from 20 to 24, and valve 40 stays closed from 20-22 and is open from 22-24. The valve actuating mechanisms are preferably timed from the internal combustion engine to which the pump is connected; and for the purpose of understanding the invention, the valve mechanisms do not need to be described here. The hot exhaust gases flow into the pump 32, filling up more and more the upper part of its space. Due to the very high temperature and very low specific gravity, the hot gases float on top of the cold original gas content and finally will occupy the upper part of the pump space above an imaginary dividing line 42, as shown in Fig. 5. The exact location of stratum 42 depends on the timing of the opening of valve 40. During this filling process the cold gases, consisting partly of previous exhaust gas cooled down and partly of fresh air previously sucked into the pump 32 (Fig. 3), are compressed into the lower part of the pump chamber, with their pressures correspondingly rising. The exhaust gas which is cooled down may be considered as occupying now the space between the imaginary dividing line 42 and an imaginary dividing line 44 below which the compressed fresh air lies, and which is identical with the imaginary dividing line 34. Cooling unit 46 during this period is moving through its downward position. The filling process continues until the pressure within the pump 32 has reached a balance with the gas pressure desired in a transfer line 50 for the cold gases. The admission line 48 is provided with baffles (Fig. 10), and adjacent the entrance to the pump are additional baffles.

During the discharge and expansion period 22-24-26 (Figs. 1, 2, 6 and 7) the admission valve 36 stays open from 22-24 and is closed from 24-26. The efflux of cold gases begins at 22 by way of the valve 40 through a line 50 toward, for example, a nozzle box of a turbine such as disclosed in my copending application, Serial No. 240,017 filed concurrently herewith for "Gas turbine system." The pressure 22-24 stays constant as shown in Fig. 1 if the admitted volume of exhaust gases covers the volume of the discharged cold gases. Obviously only the cold gas portions contained in the lower half of the pump 32 are affected by this discharge process, and they are the fresh air and the previous exhaust gas cooled down. Simultaneously, beginning from the point 24, the hot exhaust gas above the imaginary line 42 of Fig. 5 expands until its volume has increased sufficiently to fill up the total pump space including the lower zones which were occupied formerly by the cold gases. The valve 38 is closed all the time 20-26, valve 36 is closed at 24, and valve 40 is also closed at 26. By the time this process is finished, the pressure inside the pump will have dropped to atmospheric, and any further efflux ceases at 70

point 26 with no additional weights of gas discharged.

During the cooling or condensing period 26—28—30 (Figs. 1, 2, 8 and 9), the valve 40 stays closed and the cooling unit 46 is moved into its uppermost position. A fan 52 (Fig. 10) of the cooling unit 46 begins to rotate and produces a rapid circulation of the hot gases through a radiator 54, whereby the hot gases are rapidly cooled. 10 Consequently the gases inside the pump begin to shrink in volume at the rate that heat is taken from them by the water inside of the cooling unit. The water (Figs. 10, 11) enters unit 46 through an inlet pipe 56 and exits through an outlet pipe 58. This process may be considered the equivalent of the condensing process in a steam condenser. It will be highly efficient because the warmer portions of the gases automatically move up into the upper portions of the pump, thus admitting to the cooling unit 46 just those portions of the gases which are most susceptible to the cooling, while the cold gases flow to the lower zones of the pump 32.

The shrinking process results in setting up 25 within the pump a partial vacuum down to the point 28 of Fig. 1. The suction valve 38 is then opened and atmospheric air, or a portion of the previous cold gas discharge, is redrawn into the pump 32, for example by way of a gas turbine, 30 performing another filling process until the inside pressure balances again with the atmosphere outside. When the secondary filling process is finished at 30, the lower two-thirds of the pump 32 (Fig. 9) is filled up below the imaginary dividing line 34 with the redrawn air or former cold discharge; and the upper one-third of the gases above the imaginary, dividing line 34 is made up of cooled exhaust gas residue. As these residual gases are still somewhat warmer and 35 lighter in weight than the redrawn cold gases, they will occupy the upper third of the available space without substantially any diffusion as the process is carried out. Meanwhile, the cooling apparatus 46 has been rotated down again 40 into its neutral position (Fig. 3) by suitable mechanism which need not be described for the understanding of the invention, and the fan 52 has been stopped. At this point, the cycle is 45 finished and the new influx of hot gases as previously disclosed may start again. The cycle may be repeated indefinitely.

The foregoing description of the cycle, of course, merely covers the theoretically desired sequence of cyclic steps, and discloses how by 50 such operation, a turbine wheel may remain completely shielded from hot gases. Naturally in actual operation there are unavoidable transfers of heat by radiation and conduction from the hot gases to the cold gases and consequently 55 a turbine wheel may be passed by gas streams of somewhat elevated temperature levels. In order to obtain best turbine efficiency it may be even advantageous to operate the power unit purposely by gases moderately warmer than atmospheric air.

It will be obvious that the breather pump may be operated over only a portion of the complete cycle of Fig. 1. For example the cooling and breathing portion of the cycle may be used, or 60 this portion of the cycle may be omitted and the pump scavenged with air immediately after the displacement portion of the cycle is completed.

Figs. 10 and 11 disclose a suitable design of breather pump, and in my copending application, Serial No. 240,016, filed concurrently here-

with, there is disclosed other suitable pump designs. In the modification shown in Figs. 10 and 11 the cooling unit 46 is rotatably mounted within the pump and timed to make one complete revolution during each cycle. It is 5 preferable to have a variable speed of rotation of the cooler 46 so that it may pass slowly through its top and bottom positions, or even stop in these positions, and may move at greater speed between these two positions. 10

There are definite reasons for the choice of a location of the cooling unit or recuperator 46 during the several cyclic periods, as shown in Figs. 3, 5, 7, and 9. The hot exhaust gases flowing into the pump are supposed to stay hot during all 15 the period 20—22—24—26. Therefore it is desirable to provide a very efficient insulation against heat exchange with the walls, and to have the cooling unit 46 out of direct contact with the hot gases. On the other hand, the cold 20 gas content of the pump tends to become warmer due to the compression from 20—22, and it is then advantageous to move the cooling unit during that period down into the cold gases to keep them cool. These requirements are met by the 25 arrangement as shown in Figs. 3 and 5. On the other hand, during the cooling period 26—28, the cooling unit must be in the upper ranges of its motion.

In Figs. 10 and 11, fans 52 and 64, are shown. 30 The upper fan 52 is needed under all circumstances, whereas the lower fan 64 could be dispensed with. At any rate, the lower fan should cause only a gentle circulation of the lower strata of the pump content through the cooling system. 35 However, the upper fan must be able to circulate the whole pump content several times a second through the cooling unit in order to keep the duration of the shrinking period 26—28 down to a small proportion of a pump cycle period. The 40 cooling unit 46 in the pump 32 consists of a recuperator or radiator 54, and fans 52 and 64 positioned respectively at the top and bottom of the pump.

Admission and removal of cooling water or 45 other cooling fluid to unit 46 is effected respectively through inlet pipe 56 and an outlet pipe 58. These pipes are arranged concentrically and journaled to provide a suitable rotatable shaft mounting for the honeycomb radiator 54. 50

The fans 52 and 64 are preferably rotated from the power unit and timed for operation only when the cooling unit is in position in front of the fans. The fan 52 will operate therefore when the cooling apparatus 46 is in its upper position, 55 but it will not operate when the cooling apparatus 46 is in its lower position although the fan 64 will then operate. The fans 52 and 64 may be operated through suitable clutches 78 and 80 respectively and bevel gearing 86 and 88. Suitable clutch mechanisms 90 and 92 serve for actuating clutches 78 and 64 for throwing the fans in and out of operation. The clutches are timed from the prime mover.

The apparatus for operating the valves, fans 65 and cooling apparatus of the pump 32 (Figs. 10 and 11) is driven from a shaft 98 which may be operated from a prime mover, the exhaust gas from which may be delivered to the pump. The rotational speed of the main shaft carrying 70 the cooling unit inside the pump, or in other words the relative duration of one pump cycle, depends on the number of pumps making up the power plant and upon the relative ratio of aggregate piston displacement and pump volume. 75

The shaft 98 is connected by chains 100 and 102 running over sprockets 104 and 106 and sprockets 108 and 110, to shafts 112 and 114, which are in turn connected to and disconnected from shafts 116 and 118 by the clutches 78 and 80, respectively.

The combined inlet pipe and shaft 56 by which the cooling apparatus 46 is rotated is actuated from the shaft 98 by a chain 120 running over a sprocket 122 secured to the shaft 56 and a sprocket 124 which is connected to the shaft 98 by a clutch 126, which is in turn operated in a predetermined cycle from a cam 128 secured to the shaft 98. The shape of the cam groove is preferably such that the cooling unit 46 remains in its upper and lower positions for a predetermined portion of the cycle, as has been previously described. A clutch fork 130 serves to operate the clutch 126 from the cam 128. Shaft 56 is shown as mounted substantially coaxially within the pump 32.

The mechanism for operating the valves 36, 38 and 40 comprises an upper jack shaft 132 and a lower jack shaft 134. The upper and lower jack-shafts 132 and 134 are connected to cam-shafts 136 and 138, respectively. The valves 36, 38 and 40 are actuated in a predetermined cycle, as has been previously explained, by rocker arms 140 and 142 from the cam shafts 136 and 138. The jack-shafts 132 and 134 are driven from the shafts 112 and 114 by chains 144 and 146. The clutch mechanisms 90 and 92 for throwing in and out of operation the clutches 78 and 80 for operating the fans, are actuated by cams 148 and 150 mounted on the shafts 132 and 134.

The hot exhaust gases from the cylinders of an internal combustion engine enter the exhaust manifold at rather high velocity against a back pressure which may be in the neighborhood of 2 atmospheres, absolute. Some of the kinetic energy in the gas may be converted to heat by interposing restrictions in the path of the gas flow from the exhaust manifold 48 into the pump 32 past valve 36 (Fig. 10). Perforated plates 60 and 62 respectively, form the upper and lower plates of the pump 32 and are located inside of the pump, where they serve to help prevent turbulent intermixing of the hot and cold gases.

Circulation of gases through the cooling unit 46 in its upper position follows the paths as indicated by numerals 66 and 68. The radiator 54 is so arranged that the fan 52 discharges the gases through a housing 70 into a top opening 72 in the radiator. The gases then pass through the radiator 54 and discharge from side openings 74, 76. The radiator 54 has headers 82 which are connected to outlet 58 by pipes 84. A header 94 is suitably connected to the inlet 56 by a pipe 92. The pump 32 is designed with a substantially dumbbell section when viewed in side elevation and a cylindrical or drum section viewed in end elevation to withstand variable pressure differences from inside to outside. These drum type horizontal pumps are necessarily made heavier than the vertical type of pumps which are described in my aforementioned copending application, S. N. 240,016.

The pump which has been described may also serve as a pneumatic supercharger or air compressor. By opening an additional discharge valve 152, as shown diagrammatically in Fig. 5, which is connected to an admission line 154 of an internal combustion power unit, as disclosed in my aforementioned copending application S. N. 240,017 filed concurrently herewith, and by keep-

ing on admitting more hot exhaust from 22 well beyond 24 to about half way between 24 and 25, all the cold fresh atmospheric air can be delivered in a compressed state to the admission line 154 and from there into the power unit for supercharging said power unit. After the valve 152 is closed, the valve 40 may be opened and the discharge process may continue with a simultaneous expansion of the cold residue and the hot gases.

The preferred embodiments of the invention herein described are capable of certain modifications without departing from the scope of the invention to be defined in the following claims.

The invention having been thus described, what is claimed as new is:

1. The method of transferring energy from a body of hot gaseous products of combustion which comprises, introducing the gas into a chamber and trapping the gas therein after its pressure has reached substantially atmospheric, positively circulating the trapped gas within the chamber and simultaneously circulating a cooling fluid through the chamber in indirect heat transfer relation with the hot gas to reduce the temperature of the gas, thereby developing a partial vacuum within the chamber, and utilizing the vacuum thereby developed to induce influx of gas into the chamber from an outside source under higher pressure.

2. The method of utilizing the energy in a body of hot fixed gases under superatmospheric pressure which comprises, admitting a stream of said hot gas into a vessel which is filled with cold gas at substantially lower pressure, thereby displacing the cold gas and imparting energy thereto and forcing the efflux of same from the vessel, expanding the hot gas within the vessel to substantially atmospheric pressure, trapping the hot gas within the chamber, positively circulating the trapped hot gas and simultaneously circulating a cooling fluid through the vessel in indirect heat transfer relation with the hot gas to reduce its temperature and develop a partial vacuum, and utilizing the vacuum thereby developed to induce flow of cold gas from an outside source under higher pressure.

3. The method of utilizing the energy content of a body of hot gases under superatmospheric pressure which comprises, introducing the hot gas into the upper part of a vessel filled with cold gas under substantially atmospheric pressure, compressing the cold gas into the lower part of the vessel by displacement action of the hot gas while trapping the cold gas against escape from the vessel, circulating a cold fluid in indirect heat transfer relation to the cold gas undergoing compression to cool it, discharging the cold gas from the lower part of the vessel under pressure while expanding the volume of the hot gas to fill the vessel and expanding the hot gas within the vessel to substantially atmospheric pressure, and reducing the gas temperature while trapped within the vessel, thereby developing a partial vacuum, and utilizing said partial vacuum to induce influx of cold gas into the vessel from an outside source under higher pressure.

4. The method of transferring energy from a body of hot gases under superatmospheric pressure to a body of cold gas enclosed in a vessel at substantially atmospheric pressure, which comprises introducing a flowing stream of said hot gas into the top of the vessel above and in direct contact with the cold gas, baffling influx of the hot gas to the vessel and thereby promoting density

- stratification of the hot and cold gases within the vessel as the hot gas displaces the cold gas, utilizing the energy thereby imparted to the cold gas to force the same from the lower part of the vessel, expanding the hot gas within the vessel down to substantially atmospheric pressure, transferring heat energy retained by the hot gas to a second body of cold fluid by circulating said fluid through the vessel in indirect heat transfer relation with the hot gas, thereby shrinking the gas and developing a partial vacuum within the vessel, and utilizing the vacuum thereby developed to induce flow of a third body of cold gas from an outside source under higher pressure.
5. The method of compressing and pumping cold gas which comprises, trapping a body of such gas in a vessel at substantially atmospheric pressure, introducing hot gas under superatmospheric pressure into the top of the vessel above and in direct contact with the cold gas thereby displacing the cold gas downwardly while maintaining density stratification of the hot and cold gases, discharging the compressed cold gas from the lower part of the vessel at substantially constant pressure while continuing the introduction of hot gas thereto, after the cold gas has been removed discharging part of the hot gas from the vessel to expand the retained balance thereof to substantially atmospheric pressure, trapping the remaining hot gas within the vessel while cooling it by indirect heat transfer to a body of cooling fluid circulating through the vessel thereby developing a partial vacuum within the chamber, and utilizing the vacuum thereby developed to create influx of gas into the vessel from an outside source under higher pressure.
6. The method of regenerating energy from a rapidly moving body of hot gas under superatmospheric pressure which comprises converting part of the kinetic energy into heat by flowing the gas past flow restrictions, imparting pressure energy of the hot gas to a body of cold gas by introducing the hot gas into a vessel enclosing the cold gas thereby displacing the cold gas and forcing it out of the vessel while expanding the hot gas down to substantially atmospheric pressure, trapping the hot gas within the vessel while transferring heat energy therefrom to a body of cold fluid by circulating said fluid through the vessel in indirect heat transfer relation with the hot gas, and utilizing the partial vacuum developed by the shrinkage in volume of the hot gas to induce flow of a further volume of cold gas into the vessel.
7. The method of transferring energy from a body of hot gas under superatmospheric pressure to a plurality of bodies of cold fluid which comprises, trapping one of said bodies of cold fluid in a vessel at substantially atmospheric pressure, introducing a flowing stream of said hot gas into the upper part of the vessel above and in direct contact with the cold fluid thereby displacing the cold fluid downwardly while maintaining density stratification of the hot gas and cold fluid and compressing the cold fluid, discharging part of the compressed cold fluid from the vessel at substantially constant pressure and discharging the balance of the cold fluid from the vessel at a gradually reducing pressure while allowing the hot gas in the vessel to displace the cold fluid and expand to atmospheric pressure, trapping the hot gas while circulating a second body of cold fluid through the vessel in indirect heat transfer with the hot gas to lower the temperature of the hot gas and thereby shrink its volume and create a

partial vacuum within the vessel, and utilizing the vacuum thereby developed to induce influx of a third body of cold fluid into the vessel from an outside source under higher pressure.

8. In compressing and pumping cold air, the steps comprising trapping a body of said air in a vessel under substantially atmospheric pressure, introducing into the top of said vessel hot gaseous products of combustion under low superatmospheric pressure, displacing the air in the upper portion of the vessel with the hot gas and thereby compressing the air while maintaining density stratification of the air and gas layers, suspending the introduction of hot gases and discharging the compressed air from the vessel while expanding the hot gases to fill the vessel, and scavenging the vessel with a new supply of air before repeating the cycle.

9. In compressing and pumping cold air, the steps comprising, trapping a body of said air in a vessel under substantially atmospheric pressure, introducing into said vessel at one side thereof a stream of hot gaseous products of combustion under low superatmospheric pressure, displacing the air at that side of the vessel with the hot gas and thereby compressing the air while maintaining density stratification of the air and gas layers, continuing the introduction of hot gases in the vessel while discharging the air therefrom under substantially constant pressure, suspending the influx of hot gases and discharging part of the hot gases previously introduced to reduce the gas pressure within the vessel to substantially atmospheric, and thereafter scavenging the vessel with a fresh supply of air before repeating the cycle.

10. In a gas pump, a chamber having enclosing walls, a valved gas inlet opening into the top of the chamber, another valved gas inlet and a valved gas outlet ported out in the bottom of the chamber, a recuperative cooling element mounted within the chamber and having connections for circulating therethrough a cooling fluid, and mechanism for actuating and timing the operations of the valved gas inlets and outlet.

11. A gas pump comprising a chamber having a pressure differential resistant enclosing wall construction, a gas inlet ported out in one side of said chamber, a conduit for conducting to said inlet hot gaseous products of combustion under pressure, a gas inlet and a gas outlet ported out in the opposite side of said chamber, valves for controlling each of said gas inlets and outlets, means arranged to periodically develop a partial vacuum within said chamber, and actuating and timing mechanism for operating the valves and vacuum developing means.

12. In a fluid pump, a chamber having an enclosing wall construction adapting it as a pistonless pump operable in one cycle both above and below atmospheric pressure, a gas inlet ported out in the top of said chamber, another gas inlet and a gas outlet both ported out in the bottom of said chamber, valves for controlling the operation of each of said gas inlets and gas outlet, a recuperator mounted within said chamber and having associated therewith means for simultaneously circulating a cooling fluid from an outside source and gas from within said chamber therethrough, and actuating and timing mechanism for operating the gas inlet and outlet control valves and the gas circulating means.

13. Apparatus as defined in claim 10, together with a gas circulating element mounted within

said chamber and connected in operative relation with said recuperator cooler.

14. Apparatus as defined in claim 11 in which the chamber element of the pump has a substantially cylindrical cross section viewed in vertical end elevation, and a substantial dumbbell shape viewed in side vertical section.

15. Apparatus as defined in claim 11 together with baffling elements disposed in the path of gas flow into the chamber.

16. Apparatus as defined in claim 10 in which the cooling element is movably mounted whereby it may be shifted in location within the chamber.

17. A fluid pump comprising a chamber of substantially cylindrical shape disposed with its major axis horizontal, a gas inlet ported out into the top of the chamber, a gas inlet and a gas outlet both ported out in the bottom of the chamber, a recuperator cooling unit rotatably mounted within the chamber on a horizontal shaft disposed coaxially of the chamber's major axis, pipe connections for circulating cooling fluid from an outside source through the cooling elements of the recuperator, mechanism for circulating gas stored within the chamber through the cooling elements of the recuperator, and actuating and timing mechanism for controllably operating said cooling unit, and gas circulating mechanism.

18. In compressing and pumping cold air, the steps comprising trapping a body of said air in a vessel under substantially atmospheric pressure, introducing into the vessel at one side thereof a stream of hot gaseous products of combustion under low superatmospheric pressure, displacing the air from that side of the vessel with the hot gas and thereby compressing the air by stratification displacement, circulating a cold fluid in indirect heat transfer relation to the air undergoing compression to cool the air, discharg-

ing the compressed air from the opposite side of the vessel and expanding the hot gases to fill the vessel, and scavenging the vessel with a new supply of air before repeating the cycle.

19. In compressing and pumping cold air, the steps comprising trapping a body of said air in a vessel under substantially atmospheric pressure, introducing into the vessel at one side thereof a stream of hot gaseous products of combustion under low superatmospheric pressure, thereby displacing the air at that side of the vessel with the hot gas and compressing the air by stratification displacement, introducing the flowing gas stream to the vessel in a direction and at a velocity such as to insure against substantial intermixing of the air and gas except at their plane of contact, discharging the compressed air from the other side of the vessel and expanding the hot gases to fill the vessel, developing a partial vacuum within the vessel, and using said vacuum to scavenge the vessel with a new supply of air before repeating the cycle.

20. In compressing and pumping cold gas, the steps comprising trapping a body of said gas in a vessel under substantially atmospheric pressure, introducing into the vessel at one side thereof a stream of hot gaseous products of combustion under low superatmospheric pressure, thereby displacing the cold gas at that side of the vessel with the hot gas and compressing the cold gas, discharging part of the compressed cold gas from the opposite side of the vessel at substantially constant pressure and discharging the balance of the cold gas at a gradually reducing pressure after suspending the introduction of hot gases, expanding the hot gases to fill the vessel and scavenging the vessel with a new supply of cold gas before repeating the cycle.
